TRANSMITTING SYSTEM

Frank W. Jackson, Chicago, Ill., assignor to S. H.
Couch Company Inc., North Quincy, Mass.

Continuation of abandoned application Serial No.
717,607, March 27, 1934. This application No-
vember 21, 1939, Serial No. 305,442

6 Claims. (Cl. 177—380)

This is a continuation of my abandoned co-
pending application Serial No. 717,607.

The present invention relates to electrical calling
systems and more particularly to automatically
controlled call and paging apparatus that is
normally maintained in a dormant condition
but which is immediately rendered responsive to
a call setting under the control of a switchboard
operator.

It is contemplated, in accordance with the pro-
visions of this system, to be able to toll call
signals in predetermined combinations or permuta-
tions, which signals may be made audible
throughout a plant or factory site and to indicate
thereby to certain individuals, each in accord-
ance with a call designated to him, certain pre-
determined information such as, for example,
that the presence of an individual whose call is
being tolled is requested.

In addition to the apparatus provided for at-
taining the foregoing object, certain other auxiliary
apparatus is provided with the present system
for attaining other objects in addition to the
foregoing, such as, for example, for announcing
general alarm signals, dismissal signals, and the
like.

It is accordingly an object of the present in-
vention to provide a call system for issuing paging
signals, dismissal signals, and general alarm sig-
nals, and for providing means in association with
the system.

In accordance with the following description,
the features of this invention will be described in
contemplation of the certain objects set forth,
though it will be evident that in accordance with
the novel provisions thereof, many other and
equally important objects may be obtained not
specifically contemplated.

In accordance with the preferred embodiment
of this invention, there is provided a switchboard
and a plurality of switch elements illustrated in
the accompanying drawings as co-operating jack
and plug members. Each jack is labeled with
an indicia corresponding to the signal which it
is adapted to control. When a plug is inserted
into one of these jacks, a corresponding one or
ones of a plurality of contacts is opened, setting
up a condition among a series of tolling circuits
whereby various paths are established or pre-
pared, while at the same time an operating motor
is started. The motor is designed to rotate
a drum member upon the periphery of which are
carried a plurality of projections staggered pro-
gressively thereon and successively brought into

co-operation with an associated wiper or con-
tact blade.

As each projection engages its associated con-
tact blade, the aforescribed prepared circuits
are closed, causing to be energized one or more
toll sounding bells located at various points
throughout the area to be served by the system.
As long as the particular jack is in the operated
position, the operating motor continues to drive
the coding drum, causing the signal to be re-
peated until the plug is removed. The coding
drum is provided with the projections as afore-
described, arranged in a certain spaced relation-
ship so as to permit of a measured time interval
between successive toll signals. The relationship
is governed by the speed of rotation of the coding
drum, but more generally by the frequency of op-
eration that is most easily comprehensive, or
in other words, where the signals are made up of
certain combinations of numbers the tolling fre-
quency is preferably governed by a speed suffi-
ciently great enough to attain the desired object
in as short a space of time as possible, yet slow
enough so that the number of toll signals as well
as the relationship of several sets of toll signals
where combinations of them are designated as
predetermined signals may be easily compre-
hended by untrained ears with sufficient cer-
tainty, and so as to avoid confusion of signals.

30 In addition to the aforementioned projections
on the coding drum, there are also certain auxil-
iary projections provided arranged in rapid suc-
cession, which projections function to inaugurate
special signals and such as may be distinguished
35 from the coding signals and such as may be iden-
tified in accordance with predetermined arrange-
ments for the purpose of dismissal, fire alarm, and
the like.

Since it may be desirable, under certain con-
ditions, to supersede certain ones of said signals
already in the progress of transmission with other
ones either specifically or in accordance with their
class, the system is provided with means whereby,
upon the inauguration of those signals whose im-
portance is paramount, that the preceding signals
may be at once suspended and whereby the more
important signals may be inaugurated without
further delay or without having to await the com-
pletion of said other ones of said signals whose
50 order of priority is secondary.

For a better understanding of this invention
reference will be had to the accompanying draw-
ings and to the following detailed description il-
lustrating an embodiment of the invention. In
the drawings annexed hereto similar reference

characters may be taken to represent corresponding parts in the drawings.

Figure 1 shows one form which the apparatus may take illustrating schematically contact elements and circuit connections. Figure 2 shows a circuit diagram for the complete system. Figure 3 shows a cross sectional view taken approximately on line 3—3 of Figure 1 illustrating the peripheral arrangement of the contacts on the coding drum, Figure 4 shows an elevation of the switch board corresponding to the corresponding elements indicated in Figure 2 and Figure 5 shows a detail.

The drawings of the present invention show a system embracing a limited number of code signals for the sake of simplifying the invention to make it more readily understood. It may be appreciated however that the same system may be extended to a greater number of calling signals or may embrace a fewer number if that is desired.

In the drawings in Figures 2 and 4 the codes are each represented by their corresponding number. For instance the code numbered 1 will produce one stroke of the bell or one continued short ring, depending upon the type of bell desired. The code numbered 2 will give two rings separated by a suitable space and so on for the code numbers 3, 4, 5 and 6. The code number 12 is produced by a single ring marking the number 1 followed by a longer space than between the rings for marking the count for the individual digit after which two short rings are produced indicating the number 2, thus making 1 and 2, or 12. With the connections indicated in Figures 2 and 4, it is possible to produce 20 individual numbers by single operations of the switch board 11 of Figure 4. The functioning of this switch board in connection with the diagram of Figure 2 will be explained in detail below. In Figure 4 the numbers 1, 2, 3 and so forth corresponding to the numbers 1, 2, 3 and so forth of Figure 2 are printed or engraved on the switch board beside the correspondent switch jack to be operated. When the plug is placed in any one of the switch jacks 42 (see Figure 5) on the switch board 11, it operates to open some normally closed contacts 68, 70, 72, 73, etc., and to close one normally open contact, 69 for instance, for the purpose of producing the proper code signal. The switch for this purpose may be of the type commonly used in the telephone art wherein a jack 150 entering the socket separates the closed contacts of the switch 68 against the pressure of springs 151, and at the same time bridges with the conducting ring 152, the gap between the contacts 69 which project a little into the socket and are backed by springs 153. This may be done by means of the ordinary telephone plug or by any other known means, the plug separating closed spring contacts of the normally closed contacts and bridging the normally opened contacts. In the circuit arrangement indicated in Figure 2 there is provided a code drum 43 having an insulating surface upon which are mounted contact studs 44, 45, 46, 47, 48, 49, 50 and 51, which contact studs are so connected to the conducting rings 54 and 55 through the connecting lines 56 and 52 and 53 respectively. A brush 57 takes the current from the collector ring 54 and a brush 58 from the collector ring 55 which ring is split at a point that corresponds to the starting operation for the system. At the lower end of the drum 43 as shown in Figure 2 are a group of contacts 59 spaced more closely together than

the space between the contacts 44, 45, 46 etc. all of which are uniformly spaced. The mechanical arrangement of the code drum and the operating contacts are indicated in Figure 1. In this figure it will be noted that there is provided a motor 60 which drives through a reduction gear 61 the code drum 43. On the code drum shaft 62 are mounted the conducting rings 54 and 55 which are connected as has been previously described. It should be remembered that all of the contacts on the code drum are connected to the conductor 56 and therefore to both collector rings 54 and 55. The power for the system may be supplied from a single source 63 and may operate a single bell 64 or any other type of signal device or extra bells as indicated by the lines 65 and the legends upon it. As shown in Figures 2 and 4, two additional switches may be used, 66 for the purpose of operating a dismissal signal and the switch 67 for operating a watchman signal. The dismissal signal operated by the switch 66 closes the circuit for the signal bell or alarm through the contacts 59 as will be explained later, thus producing a group of rings or signals closely following one another. The watchman signal operated by closing the switch 67 completes the signal or bell circuit through all of the contacts 44 to 51 inclusive, thus operating the signal bell successively in time intervals considerably greater than those of the contacts 59 thereby producing a signal which may be clearly distinguished from the dismissal signal.

In Figure 2 the dotted line under the code numbers 1, 2, 3, etc., indicate the contacts operated by each plug, the X marking the contacts which are normally closed and opened by the plug, and the circle indicating the normally opened contacts which are closed by the plug. Under the number of the code 1 the insertion of the plug opens the contact 68 and closes contact 69. The plug for the code 2 opens the contact 70 and closes the contact 71. For numbers 1 to 6 inclusive, only one contact each is opened, 68, 70, 72, 73, 74, 75 respectively. For the numbers in the tens, two sets of contacts are opened by the code for each plug and these are the greatest numbers that are opened for any of the signals desired. Electrical connections on the drum are made by the brushes 76, 77, 78, 79, 80, 81, 82, 83 and 84 to which respectively are connected the conductors 85, 87, 88, 89, 90, 91, 92, 93 and 94. These conductors go to the jacks on the switch board 11 of Figure 4. As indicated in Figure 2, the line 87 passes successively through 5 plugs, the line 88 through 6 plugs, the line 89 through 5 plugs, the line 90 through 4, 91 through 4, 92 through 5 and 93 through 3. With this small number of contacts, 32 in all, twenty different codes can be signaled.

All of the contact brushes 76-83 inclusive are connected to a common lead 95 and each conductor 87-93 inclusive is connected to the preceding numbered conductor, the conductor 87 being connected in a similar manner to the conductor 86. It will also be noted that in this arrangement that any code number which begins with a 1 has a normally closed contact to be opened in the second line, namely the line 87, and that each number which begins with a 2 has contacts to be opened in the third line 88, while the thirty group and the number 3 have contacts to be opened in the line 89, and the 4th group has contacts for numbers 4 and 41 to be opened in the 5th line, namely 90. In the wiring arrange-

ment these contacts provide the location for the first digits of the numbers. The second digits of the numbers are arranged in accordance with the position of the first digits of the numbers. For instance the number 12 has the normally closed contacts positioned at A and B in Figure 2 separated by two conductors 88 and 89. The number 13 has its contacts A and B separated by three conductors 88, 89 and 90 and the number 14 by four conductors 88, 89, 90 and 91, and 15 by five conductors, 88, 89, 90, 91 and 92. It will be noted that this arrangement holds for the entire code. For instance suppose the plug 12 is inserted in the opening contacts in the 12 line A and B. As the code wheel 43 rotates, the line 86 will be energized when the contact 76 passes over its drum contact 44. The line 87 which would be energized next after 86, is not energized since the contact A is opened thereby making a pause and completing for the first digit. Following this, lines 88 and 89 are energized producing the digit 2 after which no further signal is produced since the entire chain is broken by the opening of the contact B in the line 90. For example another number will be taken to indicate that the same procedure holds. Take for instance number 25. The energizing of the two lines 86 and 87 will produce the digit 2, following which a break occurs in the contact A line 88, then the next five lines 89, 90, 91, 92 and 93 will produce five rings producing the digit 5. It will be noted that in the case of the number 25, the opening of only one line is needed which produces a break between a ring of 2 and a ring of 5, thus involving all of the eight lines in the system. No number requires more than two contacts to be broken, the first, after the first group of rings, and the second after the second group of rings, providing not all of the eight lines are used. Except for the first six numbers, therefore, the two digit numbers totaling seven, namely the numbers 25 and 34 require only a single contact to be broken, all of the other numbers requiring two contacts to be broken. The circuit arrangement may be analyzed in a different manner. The system as indicated in Figure 2 is an eight system. This is minimum sum computed on the basis of the sum of the digits of any code number plus the space in between which must equal the number of conducting lines. All of these lines are connected to a single outlet conductor, namely 95 and a single inlet conductor 56. Each of these lines is successively energized by the code drum at one end permanently connected to the single line 95 at the other end through the normally closed switch contacts. The lines are connected together at this latter end in such a manner that the code will be represented by a parallel group of closed lines designating the first digit, an open parallel line to designate the space between the digits, a second series of closed lines corresponding to the second digit followed by a series of open lines if this is necessary for producing the code number. In this arrangement the last contact opened opens all the other lines of the system. For instance, the contact B in the 12 plug opens the lines 91, 92 and 93, the contact B in the 13 plug opens the lines 92 and 93, the contact 68 in the one plug opens all of the lines on the 86 lines. It will be seen therefore that the last contact to be opened in the number must be a contact in series with all of the following lines and the line 95 and the same holds also for numbers that have only a single contact plug which numbers are 1, 2, 3, 4, 5, 6, 25 and 34.

- As the drum 43 rotates and the desired contacts are made on it a circuit is completed for energizing the bell as follows. Starting with the supply 63, the circuit may be traced over the line 96, the brush 57, the ring 54, the conductors 52, 56, the contact drum, one of the lines from the contact drum to the conductor 95 to the relay contact 97, the lead 98, the bell 64 and the return line 99 to the supply 63. The system is set in operation for ringing in code as has been set forth above by the placing of the plug in the desired jack. This opens the X contacts corresponding to the code number and closes the desired O contact as for instance 69, 71, 100 etc.
- 10 The closing of the O contact energizes the motor in the following manner. This circuit may be traced from the supply 63 through the motor 60, the line 101, the O contact 100 etc., the return conductor 102, and the return to the supply 96. The motor will continue to rotate while the jack is in position in the chosen code number called. When this is removed the motor still will continue to rotate until the brush 58 has come to a position opposite the break in the ring 55, for until that time the motor circuit is completed in the following manner to wit: Starting at the supply 63, the circuit may be traced through the motor 60, the line 101, the brush 58, the ring 55 (until the circuit is broken), the conductor 53, the conductor 52, the ring 54, the brush 57 and the conductor 96. The motor stops when the brush 58 goes opposite the opening in the ring 55, thus leaving the code drum in a starting position.
- 15 The system in addition to the above provides a watchman's signal and a dismissal signal. The dismissal signal is operated by the switch 66 which closes a circuit through the relay 103 thus drawing up the armature 104 and breaking the contacts 97 but making the contacts 105 and 106. The making of the contact 105 closes the motor circuit as is seen by tracing the following circuit: the supply 63, the motor 60, the line 101, the contact 105 now closed, the line 102 and the line 96 to the supply source.
- 20 The bell circuit is also closed through the closely spaced contacts in the following manner. The supply 63, the line 96, the brush 57, the ring 54, the conductors 52 and 56, the contacts 59, brush 84, line 94, contacts 106, line 98, bell 64, line 99 to the supply source. This rings in accordance with the closed position of the contact points 59 rapid signals on the bell. When the dismissal signal switch is opened the motor will continue to function as has been explained before until the open ring 55 has its opening position opposite the brush 58 so that the drum again goes to rest in a position to be operated again.
- 25 The watchman signal is given by closing the switch 67 which energizes the motor in a circuit commencing at the supply 63 going through the motor 60, the line 101, the switch 67, the line 102 and the line 96 to the supply source. As the motor rotates and turns the drum, the line 95 will be energized as each of the brushes 76 to 83 inclusive comes in contact with the corresponding contacts on the drum.
- 30 As has been stated above these series of rings are spaced further apart than the rings produced by the contacts 59 and this therefore distinguishes the watchman's signal from the dismissal signal.
- 35 It should be noted in the arrangement of Figure 2 that when the dismissal signal is used,
- 40
- 45
- 50
- 55
- 60
- 65
- 70

the code signal is discontinued by the breaking of the contact 91, thus opening the circuit to the line 95 and the drum. In the section shown in Figure 3 the top surface of the drum 43 may be made of insulating material with a ring or cylinder beneath this of conducting material 107 and an inner ring of insulating material 108, proper contact being made with a conducting ring 107 to connect all of the surface contacts of the drum to the external conductor going to the slip rings 54 and 55.

For the purpose of establishing terms for description of the invention the parallel lines 86 to 93 inclusive may be looked upon as corresponding to successive integer and spaces of the code number; that is, the line 86 corresponds to the first integer, the line 87 to an integer or space whatever the code number may call for, and so on for each line. The line 86, for instance, will carry current for all the numbers since no number of the code in Figure 2 calls for a space at the beginning. The line 87 however corresponding to the second integer or first space, calls for a space where the first digit of the number is 1, so that it must be opened by the jacks for 1, 12, 13, 14. The line 88 calls for the third integer or space after 2 digit numbers have been sounded and thus the jacks for 2, 21, 22, 23, 24, 25 must open this line. Each line therefore corresponds to an integer making up the digit or a space, if an integer the jack keeps the line closed, if a space, the jack opens the line. The connections at the end of the parallel lines to the preceding lines must be made at a point before the last contacts so that when the last number has been finished the parallel line following corresponding to a space, when opened will open all the following lines.

In the embodiment described above, it will be noted that the contacts on the code drum energize successively the lines 86 to 93 inclusive by successive engagement of the brushes 76 to 83 inclusive. Any arrangement which accomplishes this purpose may be used as for instance a rotary contact arm. In place of the rotating drum therefore a rotary arm may be used and the fixed brushes 76 to 83 may be replaced by means of fixed contact studs. So also in place of the rotary contacts 59 another rotary arm may be used and the fixed brush 84 may be replaced by a fixed stud.

Having now described my invention, I claim:

1. In a variable transmitter for transmitting numerical electrical impulses corresponding to predetermined one or two digit numbers, the digits of the two digit numbers being separated by uniform spaces, a series of equally spaced contacts, means for sequentially energizing the contacts of the series, a direct connection from the last contact of the series to the output of the transmitter, separate connection lines, each having one end connected to the other contacts of the series, each of said connection lines including a plurality of normally closed switches and each of said connecting lines beginning with the connection for the first contact of the series having its other end connected to a point in the succeeding connection, at least some of said points being located between the plurality of switches in said connecting lines, means corresponding to the predetermined single digit numbers for opening selected single switches in predetermined connection lines and means corresponding to predetermined two digit numbers for opening combina-

tions of two switches of different predetermined connection lines.

2. In a variable transmitter for transmitting numerical electrical impulses corresponding to predetermined one or two digit numbers, the digits of the two digit numbers being separated by uniform spaces, a series of spaced contacts, means for sequentially energizing the contacts of the series at uniform spaced time intervals, a direct connection from the last contact of the series to the output of the transmitter, separate connection lines, each having one end connected to the other contacts of the series, each of said connection lines including a plurality of normally closed switches and each of said connecting lines beginning with the connection for the first contact of the series having its other end connected to a point in the succeeding connection, at least some of said points being located between the plurality of switches in said connecting lines, means corresponding to the predetermined single digit numbers for opening selected single switches in predetermined connection lines and means corresponding to predetermined two digit numbers for opening combinations of two switches of different predetermined connection lines.

3. In a variable transmitter for transmitting electrical impulses, each impulse corresponding to a unit making up predetermined one or two digit numbers, the digits of the two numbers being separated by uniform spaces, a series of spaced contacts, means sequentially energizing the contacts of the series at uniform spaced time intervals, a direct connection line from the contact at one end of the series to the output of the transmitter, separate connection lines for each of the rest of the contacts of the series, each one of said connection lines connected at one end to one of said contacts and each connected at the other end to the previous connection line of the series, each of said connection lines, except the connection line connected to the output transmitter, including a plurality of normally closed switches, the point of connection of each connection line to the previous connection line being between the location of the normally closed switches in each connection line, means corresponding to the predetermined single digit numbers for opening selected single switches in predetermined connection lines, and means corresponding to predetermined two digit numbers for opening combinations of two switches of different predetermined connection lines.

4. In a variable transmitter for transmitting numerical electrical impulses corresponding to predetermined one or two digit numbers, the digits of the two digit numbers being separated by uniform spaces, a series of spaced contacts, means for sequentially energizing the contacts of the series at uniform spaced time intervals, a direct connection from the last contact of the series to the output of the transmitter, separate connection lines, each having one end connected to the other contacts of the series, each of said connection lines including a plurality of normally closed switches and each of said connecting lines beginning with the connection for the first contact of the series having its other end connected to a point in the succeeding connection, at least some of said points being located between the plurality of switches in said connecting lines, means corresponding to the predetermined single digit numbers for opening selected single switches in predetermined connection lines and means corresponding to predetermined two digit numbers for opening combinations of two switch-

es of different predetermined connection lines, said last two means including means for simultaneously commencing the transmission of the selected number.

5. In a variable transmitter for transmitting electrical impulses, each impulse corresponding to a unit making up predetermined one or two digit numbers, the digits of the two numbers being separated by uniform spaces, a series of spaced contacts, means sequentially energizing the contacts of the series at uniform spaced time intervals, a direct connection line from the contact at one end of the series to the output of the transmitter, separate connection lines for each of the rest of the contacts of the series, each one of said connection lines connected at one end to one of said contacts, and each connected at the other end to the previous connection line of the series, each of said connection lines, except the connection line connected to the transmitter, including a plurality of normally closed switches, the point of connection of each connection line to the previous connection line being between the location of the normally closed switches in each connection line, means corresponding to the predetermined single digit numbers for opening selected single switches in predetermined lines, and means corresponding to predetermined two digit

numbers for opening one switch or a combination of two switches of different predetermined connection lines.

6. In a variable transmitter for transmitting electrical impulses, each impulse corresponding to a unit making up a predetermined number of not more than two digits, the digits of the two numbers being separated by uniform spaces, a series of spaced contacts, means sequentially energizing the contacts of the series at uniform spaced time intervals, a direct connection from the last contact of the series to the output of the transmitter, separate connection lines each having one end connected to the other contacts of the series, each of said connection lines including a plurality of normally closed switches and each of said connection lines beginning with the connection line for the first contact of the series having its other end connected to a point in the succeeding connection line, at least some of said points being located between the plurality of switches in said connection line, and means corresponding to the predetermined numbers for opening one or more selected switches in predetermined connection lines whereby the predetermined number is selected.

FRANK W. JACKSON.
